UNITED STATES PATENT OFFICE.

OSKAR HELFFT, OF BERLIN, GERMANY.

DESIGN FOR AN INCANDESCENT LAMP.

No. 38,484.

Specification for Design.

Patented Jan. 29, 1907.

Application filed September 6, 1906. Serial No. 383,572. Term of patent 7 years.

To all whom it may concern:

Be it known that I, OSKAR HELFFT, a subject of the Duke of Anhalt, residing at Berlin, Germany, have invented a new, original, and ornamental Design for Incandescent Lamps, of which the following is a specification, reference being had to the accompanying drawing, forming part thereof.

The figure is a perspective view of an incandescent lamp, showing my new design.

I claim—

The ornamental design for an incandescent lamp, as shown.

OSKAR HELFFT.
